UNITED STATES PATENT OFFICE.

LOUIS A. DOUILLET, OF NEW YORK, N. Y.

DESIGN FOR THE SURFACE ORNAMENTATION OF GLOVE-BUTTONS.

SPECIFICATION forming part of Design No. 19,175, dated June 25, 1889.

Application filed April 19, 1889. Serial No. 308,900. Term of patent 14 years.

To all whom it may concern:

Be it known that I, LOUIS A. DOUILLET, a citizen of the Republic of France, residing at New York, in the county and State of New

5 York, have invented a Design for the Surface Ornamentation of Buttons to be Used for Gloves or Similar Articles, of which the following is a specification.

10 My design, which is illustrated in the accompanying drawing, consists of a distinguishing background, which in the case of a metal button may be formed by roughening the metal, and in other buttons by any surface effect having a similar appearance. Upon 15 this background is the distinguishing feature of my design, consisting of a series of curved bars forming an open five-pointed star, each point of said star being of an elliptical shape. This star is inclosed by a circular boundary-

line, shown in the drawing as a circular band, 20 similar to that composing the outline of the star.

Referring to the drawing, the background is indicated by A, the five-pointed star by C, and the inclosing-band by B.

25 What I claim as new, and desire to secure by Letters Patent, is—

A design for the surface ornamentation of buttons, substantially as herein shown and described, having for its main distinguishing 30 feature a series of curved bars forming an open-pointed star, the said bars being upon a distinguishing background and the whole inclosed by a circular boundary.

LOUIS A. DOUILLET.
